United States Patent Office

Des. 209,468
Patented Dec. 5, 1967

209,468

HOT TOP CASING

Fred Eastwood, Fairview Park, John Harry Brindle, Lakewood, and John Gardner, Cleveland, Ohio (all of P.O. Box 8728, Cleveland, Ohio 44135)

Filed July 20, 1965, Ser. No. 86,222

Term of patent 14 years

(Cl. D54—8)

FIG. 1

FIG. 2

FIG. 3

FIG. 1 is a perspective view of a hot top casing embodying our new design;

FIG. 2 is a bottom plan view of that hot top casing of FIGURE 1; and

FIG. 3 is a top plan view of the hot top casing of FIGURE 1.

The dominant features of our design reside in the portions shown in full lines.

We claim:

The ornamental design for a hot top casing, substantially as shown and described.
